(57) **CLAIM**

The ornamental design for the unified image display for a video terminal including a gaming machine, as shown and described.

DESCRIPTION

FIG. 1 is a front-side perspective view of the display according to the present invention showing an example of content displayed thereon;

FIG. 2 is a front view of the display of FIG. 1;

FIG. 3 is a right side view of the display of FIG. 1;

FIG. 4 is a left side view of the display of FIG. 1;

FIG. 5 is a rear view of the display of FIG. 1; and,

FIG. 6 is a top view of the display of FIG. 1.

The broken lines showing portions of a terminal cabinet to support the display of the present invention in FIGS. 1-6 are for illustrative purposes only and form no part of the claimed design.

1 Claim, 6 Drawing Sheets

FIG. 2

FIG. 3

FIG. 4

FIG. 5

FIG. 6
